COMPOUND TOOL

Harry R. Gregory, Sault Ste. Marie,
Ontario, Canada

Application March 6, 1943, Serial No. 478,280

4 Claims.

(Cl. 306—42)

This invention relates to compound tools and more particularly to brickmasons' hammers, which include a hammer head and a blade or bit.

An object of the invention is to provide a brickmason's hammer, with its compound head made up of only two sections, detachably secured together, whereby the blade section may be removed for grinding, renewal or substitution of another size or shape of blade.

Another important object is to provide a novel means for detachably securing together a hammer head section and a blade section, with the means including a portion overlapping both sections, whereby a particularly sturdy joint is provided.

Still another object is to provide a double bevel joint between the two sections of the novel hammer. With the joint provided, coupled with the means for securing the two sections together, there is substantially no tendency for the tool to fracture at the joint.

Other objects and advantages of this invention will be apparent during the course of the following detailed description, taken in connection with the accompanying drawing, and in which drawing.

Figure 1 is a vertical section of the novel compound tool.

Figure 2 is a top plan thereof, assembled.

Figure 3 is a top plan of the blade section disassembled.

Figure 4 is a top plan of the hammer section, also disassembled.

Figure 5 is a fragmentary bottom plan of the novel tool, with handle portion in horizontal section.

In the drawing, wherein for the purpose of illustration is shown a preferred embodiment of the invention and wherein similar reference characters designate corresponding parts throughout the several views, the letter A may designate the novel compound tool, B the hammer section thereof, C a tool, such as the blade section, D means for detachably securing together sections B and C, and E a handle section.

The hammer section B is of one piece, of any approved metal, and includes a hammer head 10, which may present a substantially flat, forward, striking surface or face 11. The section B has an upper face 12, curved if preferred, a bottom face 13 and a stepped beveled portion 14 at its end opposite the head 10. Intermediate the head 10 and portion 14 is a handle-receiving portion 15 preferably provided with a suitable opening 16 to receive one end of the handle section E.

With reference to the stepped beveled portion 14, which is of novel construction, there are provided two beveled faces, the upper one 17 extending downwardly from the upper face 12 and, preferably, inwardly toward the head 10. Next, at the base of the face 17 is a shoulder 18 extending away from the head 10 and providing a substantially flat upper face 19 with its lower face comprising a portion of the bottom face 13. From the outer end of the face 19 of the shoulder 18 extends downwardly and toward the head 10, a second or lower beveled face 21. Preferably, the beveled faces 17 and 12 parallel each other.

Thru the shoulder 18 from its upper face 19 to the face 13 extends an opening, such as the perforation 22, and into the upper face 12 extends a recess 23, preferably U-shaped, with the curved portion of the recess disposed nearest the head 10. This recess also opens into the beveled face 17, and the functions of this perforation and recess will be later described in detail.

Now, as for the tool C, which is shown as a blade or bit section 25, this is of one piece with an upper face 26 which, when the compound tool A is assembled, merges into the face 12, a bottom face 27, a sharpened end portion 28 and a stepped beveled end portion 29 opposite the portion 28.

With reference to the stepped beveled portion 29, this is of novel construction, and presents two beveled faces, the upper beveled face 30 extending downwardly from the upper face 26 and, preferably, away from the end portion 29. Below the base of the face 30, is a flattened face 31 extending toward the end portion 29 and at its inward end is the second beveled face 33 which extends downwardly and, preferably, away from the end portion 29, paralleling the face 30.

Into the upper face 26 extends a recess 34, preferably U-shaped with the curved portion of the recess disposed nearest the end portion 28. This recess 34 also opens into the beveled face 30. At the bottom of the recess 34 is a perforation 35 extending to the flattened face 31, all for a purpose now to be described.

Means D for detachably coupling or connecting the sections B and C together preferably includes a bolt having a special head 40, oval in plan and of substantially the same depth as that of the recesses 23 and 34. The shank 41 of the bolt is preferably screw-threaded at its free end and may be long enough to extend thru the perforations 22 and 35. A suitable nut 42 for the shank 41 may be provided and a lock washer 43.

The beveled faces 17 and 30 are adapted to

be in intimate face-to-face contact when the sections B and C are placed together, as in Figures 1 and 2, as are likewise the beveled faces 21 and 33. In addition, the flattened face 31 is adapted to be in face-to-face contact with the flat upper face 19 of the shoulder 18. When so assembled, the perforations 22 and 35 align and the two recesses 23 and 34 form a single recess, oval in shape, as shown in Figure 2, which is adapted to snugly accommodate the head 40. Being of this shape, the bolt will not turn when the head is in the last-named recess and the nut 42 may be readily tightened or loosened.

It will be noted in Figure 1 that this head 40 overlaps portions of both the sections B and C and this novel assembly provides a particularly strong construction, coupled with the stepped-beveled face-to-face contact of the sections B and C. The head 40 due to its elongation is so socketed in the sections B and C as to prevent turning thereof incidental to removal or tightening of the nut.

Being readily disconnected, the section C, which may take various shapes as to its end portion 28, may be replaced by a bit or blade of different free end, or the tool C removed in order to be drawn out or resharpened. It is also apparent that a workman need carry but one hammer section B, with handle E, and selected kinds of tools C, instead of a multiplicity of brickmasons' hammers with various styled bits permanently attached thereto.

The handle section E is, of course, conventional and is shown as extending into the opening 16 at one end but, insofar as the novelty in this invention is concerned, could be integral with the section B.

Various changes may be made to the shape, size and arrangement of parts without departing from the spirit of the invention or the scope of the following claims.

I claim:

1. In a brickmason's hammer, a hammer section, a blade section and means detachably securing said sections together, including a bolt with the shank thereof extending thru said sections and the head thereof overlapping and in intimate contact with both of said sections.
2. In a brickmason's hammer, a hammer section, a blade section, each section being provided with a recess, with said recesses cooperating, when said sections are assembled, to provide a single recess, and means detachably securing together said sections when assembled, including a bolt with the shank thereof extending thru said sections and the head thereof disposed in

said single recess and overlapping both sections at the base of said single recess.

3. In a compound tool, a hammer section provided with an upper face, a head at one end and a stepped beveled portion at the opposite end, having a beveled face extending downwardly from the upper face of said hammer section and inwardly towards said head, a shoulder extending from the base of said beveled face away from said head, a second beveled face extending from the outer end of said shoulder downwardly and substantially paralleling said first-named face, and with said shoulder provided with a perforation, and a substantially U-shaped recess in said upper face, opening at said upper face and at said first-named beveled face; a tool at the opposite end of said hammer section, having an upper face, a stepped bevel portion provided with two beveled faces in intimate contact with the beveled faces of said hammer section, a perforation aligned with said first named perforation, and a substantially U-shaped recess in the upper face of said tool opening at said last named upper face and at the uppermost of the beveled faces of the stepped beveled portion of said tool, said second named perforation opening at the base of said second named recess; and means detachably securing said tool and hammer section together with said beveled faces in intimate contact, comprising a bolt having a head snugly accommodated in said recesses, a screw-threaded shank extending thru said perforations and depending below the same and a nut upon said depending portion.

4. In a detachable bit section of a brickmason's hammer which is provided with an upper face, a stepped beveled portion at one end comprising two beveled faces, and a shoulder, a perforation thru said shoulder and a recess opening into said upper face and into the upper of said beveled faces, said bit section comprising a bit portion at one end and a connecting portion at the opposite end having an upper face, with said connecting portion provided with two beveled faces fitting against said first-named beveled faces, a recess opening into said last named upper face and into the upper of said last named beveled faces, and an opening at the base of said last-named recess, aligning with said perforation when said beveled faces are in contact and said recesses open into each other at said beveled faces, whereby said recesses provide a recess for a headed portion of a coupling means and said opening and perforation, accommodate a shank portion of said coupling means.

HARRY R. GREGORY.
